UNITED STATES PATENT OFFICE.

EWALD C. GLITZKE, OF KANSAS CITY, MISSOURI.

CONTROL FOR ELECTRIC FURNACES.

Application filed November 19, 1926. Serial No. 149,323.

This invention relates to improvements in electric furnaces, and refers more particularly to the method of controlling and regulating the furnace temperatures within the 5 muffle of an electric furnace.

Among the important objects of the invention are, to provide a fusible wire interposed in the circuit supplying current to the resistor or resistance wire heating coil which 10 will fuse at a predetermined temperature chosen as the temperature desired for the melting or treatment of material contained in the furnace.

The invention is described in connection 15 with a small dental electric furnace in which porcelain is fused in the making of artificial teeth, but it will be understood that the invention is as applicable to any type of laboratory or commercial electric furnace 20 where electric power is utilized as the means for heating the furnace.

Fig. 1 is a front elevational view of a dental furnace.

Fig. 2 is a side view with a portion 25 broken away, showing the muffle and positioning of the fuse wire.

Fig. 3 is an inside view of the muffle door.

Fig. 4 is a diagrammatic view of the electric circuit.

Referring to the drawings, at 1 is shown 30 an electric furnace for dental use. This furnace is mounted upon any type of suitable standard 2. The furnace consists of a cylinder of highly refractory ceramic material shown at 3 in the cut-away portion in Fig. 2. This insulating material is surrounded by a metal jacket. The muffle 4 is a small hollowed-out chamber in the ceramic material. Imbedded in the top of the muffle is 35 a resistance wire 5 shown in Fig. 2 and Fig. 4. The front of the muffle is closed by means of a muffle door 6 upon which are mounted the binding posts 7 and 8.

On the standard of the furnace is a variable resistance rheostat having contacting buttons 9 which are engaged by means of a lever 10 in order to increase the current supplied to the resistance coil or resistor element within the muffle chamber and by 40 means of which the furnace is heated. The

source of current or power is supplied through the power lines designated as 11 and 12 which are connected to the binding posts 13 and 14 of a switch. The arm 15 of the switch is pivoted on the binding post 14 55 and may be thrown to engagement with the binding post 13 or to a second binding post 16 which has connection through a line 17 with the resistance coil in the furnace. The binding post 13 is connected by a wire 18 60 upon the binding post 7 on the muffle door and the lever of the rheostat 10 is connected by a line 19 to the binding post 8 on the muffle door, while the contacting buttons of the rheostat have connection through a line 20 to the resistance wire or resistor 65 in the furnace.

It is usual practice in the heating of furnaces by electricity to have positioned within the muffle a thermocouple which is connected to a registering pyrometer in order that the operator can ascertain the muffle 70 temperatures. The thermocouple and pyrometer arrangement has been, and is, unsatisfactory where an accurate temperature is 75 desired and particularly at high temperatures, variations of considerable range are experienced, occasioned by the fact that at these high temperatures the recording pyrometer is less sensitive. Variations in the 80 current will also produce irregularities which are more or less disastrous to the maintenance of accurate muffle temperatures,—variations being troublesome in the fusion or heating of material, such as porcelain, where accurate temperatures are essential to produce the desired hardness and 85 coloring in dental work.

Under certain conditions, it is also essential 90 to bring a material gradually up to temperature and immediately discontinue heating when the temperature has arrived at a particular point which it is desirable to accurately ascertain.

Experience with recording pyrometers 95 has been so unsatisfactory that the present method of controlling these temperatures has been resorted to. In place of a pyrometer, a fusible wire 21 is connected to the binding posts 7 and 8 mounted upon the 100

muffle door and extends in a loop through holes in the door into the furnace muffle. A metal or an alloy of metals is selected which has a fusion temperature at the desired temperature which is to be reached in the muffle and the switch 15 is thrown into engagement with the binding post 16 so that the power is supplied to the heating coil—the circuit being completed by means of the switch and 10 fusible wire connecting the binding posts 7 and 8 on the muffle door. These binding posts are connected to the binding post 13 and the rheostat, respectively. The temperature is gradually raised in the muffle by 15 advancing the lever 10 successively through the range of the rheostat, across the contacting buttons, and thereby increasing the heat supplied to the muffle. Within the muffle is placed porcelain or other material to be 20 treated, designated as 22 in Fig. 2, upon a removable slab 23 of refractory material. When the temperature in the muffle has reached the fusible temperature of the wire 21, the wire is melted and the circuit broken. 25 In this manner, the temperature to which the furnace muffle is raised may be accurately determined and controlled.

Below are enumerated a number of metal combinations which have been used for the 30 regulation of furnace temperatures and with which satisfactory results have been obtained. Also, a list of metals have been selected which would fuse at somewhat lower temperatures if such temperatures 35 were desirable for purposes other than the fusion or treatment of porcelain.

*Alloys having melting point of 2300° F.
(1260° C.)*

	Per cent.	Per cent.	
Copper	90	Cobalt	10
Nickel	33	Copper	67
Nickel	78	Tin	22
Nickel	12	Lead	88
Manganese	100		
Copper	54	Silicon	46
Copper	90	Iron	10

*Alloys having melting point of 2560° F.
(1405° C.)*

	Per cent.	Per cent.	
Copper	32	Cobalt	68
Cobalt	42	Chromium	58
Cobalt	81	Chromium	19
Nickel	77	Copper	23

	Centigrade.
Copper	1098°
Cobalt	1465°
Manganese	1260° 65
Nickel	1450°
Lead	334°
Iron	1536°
Silicon	1404°
Tin	235° 70

One dental supply company at the present time furnishes porcelain identified as "low fusing", "medium fusing" and "high fusing",—the first fusing at approximately 75 1700° F., the second at 2300° F., and the latter at 2440° F.

By the use of a fusible wire of one of the selected alloys, the temperature of the muffle is maintained within a selected range and 80 there is no possibility of overheating.

This control also permits the functioning of the furnace while other work is being done,—a practice which is not permitted where the operator must rely upon pyrometer control.

As suggested, although the invention has been described in connection with dental work, it will be recognized that it is as adaptable to any type of furnace in which 90 electricity is used for heating.

A number of metals or alloys of metals have been herein suggested, but this by no means exhausts the possibility of fusible substances adapted for such use.

I claim as my invention:

1. An electric furnace control for limiting normal furnace temperature, comprising a furnace having a heating element therein, said heating element connected in an electric circuit, a closure for said furnace, binding posts, mounted on said closure and interposed in the electric circuit, a fusible element having a predetermined melting point, connecting the binding posts and completing 100 the circuit, and extending into the furnace to receive the same heat as the material undergoing treatment.

2. An electric furnace control for limiting normal furnace temperatures, comprising a furnace having a heating element therein, said heating element connected in an electric circuit, a removable closure for said furnace and connections interposed in the circuit mounted on said closure, an element fusible at a predetermined temperature between said connections completing 110 the circuit and extending through the closure into the furnace to receive the direct radiated heat thereof.

EWALD C. GLITZKE.
